UNITED STATES PATENT OFFICE.

WILLIAM G. LIEBIG, OF DETROIT, MICHIGAN.

BRUSH-MAKING MACHINERY.

1,161,394.

Specification of Letters Patent. Patented Nov. 23, 1915.

Application filed October 31, 1913. Serial No. 798,420.

To all whom it may concern:

Be it known that I, WILLIAM G. LIEBIG, who am a citizen of the United States, residing at Detroit, county of Wayne, State of Michigan, have invented a certain new and useful Improvement in Brush-Making Machinery, and declare the following to be a full, clear, and exact description of the same, such as will enable others skilled in the art 10 to which it pertains to make and use the same, reference being had to the accompanying drawings, which form a part of this specification.

This invention relates to machines for 15 making brushes, and has for its object improvements adapted to render the machine adjustable, as regards the efficiency of its operation, to variations in the thickness of the blanks or brush backs worked upon, so 20 that, as regards the depth into which each tuft of bristles is sunk into the brush back by the descending movement of the staple forming and tuft setting needle, uniformity in the work will be secured.

25 The tuft setting and needle-forming mechanism is described and illustrated only to such an extent as is necessary to disclose the complete structure and operation of the machine, the details of this feature being 30 reserved as the subject of another application.

In the drawings:—Figure 1 is a front elevation of the machine. Fig. 2 is a side elevation. Fig. 3 is a perspective of the upper 35 part of the machine, particularly the actuating shaft and cam, and the tuft locator, as well as the tuft and staple-handling parts. Fig. 4 is a plan view of the lever mechanism which supports and adjusts the height of 40 the blank rest. Fig. 5 is a side elevation, partly in section, showing the cup member and its contained eccentrics, by which the stem which supports the brush back rest is held firmly locked during the desired portion 45 of each operation of the machine. Fig. 6 is a plan view, partly in section, of the parts shown in Fig. 5. Fig. 7 is a plan view from above, of the complementary semi-circular clamping blocks which engage about 50 the stem of the brush support, disassociated from the adjacent parts. Fig. 8 is an elevational view of these blocks, with the relative position of the stem which they are to clamp and thereby support shown in dotted lines. Fig. 9 is a plan view, similar to Fig. 55 7, of the actuating wedge pieces for actu-

ing the semi-circular clamping blocks shown in Fig. 7. Fig. 10 is an elevational view of the actuating cam pieces shown in Fig. 9, similar to the elevational showing of the 60 clamping blocks in Fig. 8.

12 represents the supporting table of the device, from which rises an overreaching bracket 13, in whose top portion is journaled the power shaft 14, which receives its 65 actuation from a belt 15, or other suitable power-transmitting member, through the medium of the clutch 16. The actuating track cam 18 may be thrown into and out of operative engagement with the fly wheel 17, 70 this being regulatable by means of the bell-crank lever 19, actuating links 20 and 21, and the pivoted treadle 22; the bell-crank lever 19 is pivotally supported from a projecting bracket 23 on the main bracket 13. 75

Pivotally supported near the top of the bracket 13 is a lever 24, the forward end of which is preferably provided with a roller 25, which engages in one of the tracks 26 of the cam member 18. This track, it will be 80 noted, is by no means truly circular, but as to about one half of its length is bent inward from the circular line which would correspond, as regards its distance from the central axis, with the path of the remaining one half of the track, and in this portion of the track are certain waves or irregularities 26^a, 26^b, and 26^c, which, when reached by the roller 25, are adapted to impart a faltering movement to the lever 24 and its 90 connected parts, while also sharply depressing its forward, roller-carrying end; to the opposite end of the lever 24 from that whereon the roller 25 is carried is pivoted the upper end of the link 27, which is raised 95 by this movement just described, and whose lower end is similarly connected to one end of a knuckled lever 28, which is fixed about a shaft 29, from the opposite end of which (see particularly Fig. 4) rises the lever arm 100 30, which is pivotally connected to one end of the link 31, whose function in actuating and clamping certain of the parts will be hereinafter described.

Engaging through the table 12 and the 105 strut 32 which rises from the forward portion thereof is the supporting stem 33 of the blank support 34, on which the brush backs are rested in position to receive the tufts of the bristles from the overhanging 110 tuft-delivery member 35. Pivotally attached to the lower end of the stem 33 is the

yoke 36 at one end of the lever 37; this engages, though not rigidly, about the shaft 29, and is normally held in raised position, enough so as to similarly hold the stem 33 in yieldingly raised position, by the spring 38, which is wound around the shaft 29, one end being anchored in the drum or disk 38^a, which is fixed on the shaft 29, and the other end engaging under the lever 37 to raise it and consequently the stem 33; the rear end of this lever 37 extends beyond the shaft 29, and is formed to overhang the lever 28, so that its adjusting screw 39 may be changed in position to engage the upper surface of the lever 28 at an earlier or later period in its upward movement, as conditions may require.

The extreme forward projection of the strut 32 is bored vertically, so as to slidably receive the stem 41 of the arm support 42, the raised or lowered position of the stem 41 being regulatable through the medium of the clamp 43. From a slightly rearward portion of this strut projects a branch 25 bracket 44, resting in which is a screw or pin 45^a which supports the cupped member 45, whose vertical central axis as thus positioned is bored to permit the sliding engagement therethrough of the stem 33. Within 30 the walls of this cup are located a pair of eccentrics or cam segments 46 and 47 (see particularly Figs. 9 and 10), which are similarly rounded at top and bottom to permit the engagement between them of the stem 33, the bore, however, being slightly elliptical, as viewed from above, for a purpose which will be shortly explained. These wedge members are rendered non-rotatable with respect to the cupped member 45 by the 35 engagement of their projecting lugs 46^b and 47^b in recesses or holes bored in the interior surface of the side walls of the cupped member 45. Next within these cam segments are located a pair of complementary stem-engaging segments 48 and 49; as shown in 40 Figs. 5 and 7 these are similarly rounded or grooved along their straight edges to permit the engagement therebetween of the stem 33.

It being highly important that the brush back rested upon the support 34 shall be so accurately positioned that the tuft of bristles to be set by the vertically reciprocating tuft-delivery member 35 will be driven cleanly and directly into each bored hole in the brush back in turn, there is provided a tuft-locating member 50, which is pivoted at 50^a in the upper portion of the overreaching bracket 13, so that its hole-locating point 51 reaches below the member 35, while its upper end, carrying the roller 52, engages another track 53 on the cam member 18. This track, it will be noted, is truly circular except in one place, where the knob or projection 54 is located; when the roller 52 encounters this, the lower end 51 of the lever

50 is thrown sharply upward so as to be out of the way of the tuft-delivery member 35, which immediately begins its downward, tuft-setting movement, due to the influence of another track 56 upon its supporting slide 70 55. During the rest of the downward movement of the slide 55, and during its return movement, the point 51 merely slidably engages the side of the supporting slide 55, and as soon as it has risen high enough to permit it, engages with its tip 51 just under the tuft-delivery member 35 again. The lower point 51 of the lever 50, being at all times, except the brief actuated period just described, so far below the usual position of 80 the tuft-setting mechanism, engages the top surface of the blank in its position on the support 34, thus locating accurately the exact position of the several holes in the blank with reference to the vertical path of 85 travel of the tuft-setting mechanism, and consequently advising the operator whether any shifting of the position of the blank is necessary before the tuft-setting mechanism starts to descend.

The operation of this device, as regards the brush back support is as follows:—The cam 18 being started in rotation by pressing upon the treadle 22, the forward end of the lever 24 is depressed through that portion 95 of the rotation of the cam covered by the truly circular portion of the track 26; this results in throwing the stem 33 and its brush back support 34 to its lowest position, so as to permit the easy removal or adjustment of 100 the blank rested thereon, with respect to the tuft-setting mechanism. When, however, the interior portion 26^a of the track is reached, the forward end of the lever 24 is thrown upward, resulting in a depression 105 of its rear, and, through the medium of the connected link 27 and levers 28 and 37, the stem 33 is raised so that the brush back placed upon the top 34 is held exactly at the desired height with regard to the tuft setting mechanism; the faltering or irregular movement imparted to the lever 24, by the curves 26^a 26^b, and 26^c in the track 110 imparts a very slight though sufficiently irregular motion to the stem 34 so as to coöperate with the tuft and staple-setting mechanism in not only driving the tuft and its staple to the extreme bottom of the hole that has been previously bored in the brush back, but as well clenches the staple in the wood of the 115 block, so as to prevent its tearing out.

At one point in the stapling operation the support 34 at its stem 33 must be rigid to a degree beyond the possibility of the lever 24, link 27 and the levers 28 and 37 to accomplish this. There is therefore provided the lever 30, which derives its actuation from the movement of the lever 28, both being mounted upon the shaft 29; this lever 30 is connected through the link 31 with the cup 120

member 45, which is capable of rotation to a limited degree about its pivot 45^a as a center. The cam segments 46 and 47 being non-rotatably connected with the cup 45 through the medium of the lugs 46^b and 47^b, it is evident that whenever the cup member 45 is rotated, however slightly, these members are rotated with them, and consequently, because of their inclined inner surfaces, they influence the position of the semi-circular segments 48 and 49, with respect to the stem 33. When in non-clamping position the cam segments 46 and 47 are in such a position with respect to the members 48 and 49, and to the stem 33, that their shoulders 46^a and 47^a are nearly in alignment with the stem 33. When, however, they are caused to rotate (to the right, or clockwise in the position shown in Fig. 5) it is evident that these inturned cam surfaces will bear against the adjacent curved surfaces of the semi-circular segments 48 and 49 to force them from their position opposite one another, and truly located with respect to the cam center, to the raised and lowered positions respectively, as shown in Fig. 5, and not only are the cam segments raised and lowered respectively, but each segment is forced slightly inward, to an extent sufficient to change the loose or slidable relations of their bored or hollowed out straight edges with respect to the stem 33 to a closely seizing or clamping position thus obtaining the desired absolute rigidity of the brush-back support 34 at the moment of impact of the staple against the bottom of the bore in the brush back. The continued travel at the cam 18 with respect to the roller 25 on the lever 24 then causes the forward end of the lever 24 to descend again, resulting in depressing the rear end of the lever 28, causing a backward movement in the lever 30, consequently a retracting movement of the link 31, and thereby releasing the clamping seizure of the segments just described, which an instant after this releases the stem 33, permitting the drop of the yoke end 36 of the lever 37 to again lower the stem 33, as already described.

I have illustrated a construction in which, in order to have the power cam as near and as directly connected with the tuft-setting and staple driving parts as possible, the operative connection thereof with the parts near the bottom of the machine has been through the medium of the links and lever members described. It is of course to be understood, however, as clearly within the scope of my invention to use other and equivalent operating means, differently arranged if necessary to secure corresponding efficiency of operation.

What I claim is:—

1. In a brush making machine, in combination with means for gathering and set-

ting tufts of bristles, a vertically adjustable support for a brush back during the tuft-setting operation, a pivoted lever member with one end of which said support is connected, a pair of clamping blocks between which said support slidably engages, a second lever member whereby said clamping blocks are forced against said support to hold it against movement during a certain period in each cycle of operations, and actuating members for each of said lever members and their connected parts, for moving each lever in timed relation to the movement of the other lever and of the tuft-handling mechanism.

2. In a brush making machine, in combination with a power shaft, a tuft-setting and staple-driving mechanism operatively connected therewith, an adjustable support for brush backs, a pivoted lever operatively connected with said support and by whose movement it is raised and lowered, a pair of clamping blocks with respect to which said support is normally slidable, means for forcing said clamping blocks into locking engagement with said support, and link and lever mechanism operatively connected with said power shaft and from which said pivoted lever and said block-forcing means derive their actuation in desired sequence with respect to one another and to the staple-driving mechanism.

3. In a brush making machine, the combination of a frame member, a brush back support capable of vertical movement with respect thereto, a power shaft, power-transmitting means operatively connected therewith, a pivoted lever deriving its actuation from said power-transmitting means, whereby said support is raised and lowered at desired periods in the cycle of operations, and a pair of clamping blocks also operatively connected with said power-transmitting means, and between which said support normally slides freely, adapted to be forced into locking engagement with said support when the same has been raised by its lever to the desired elevation, and to be thereafter positively withdrawn from such locking position, substantially as described.

4. In a brush making machine, the combination, with a power shaft, of a plurality of series of power-transmitting members operatively connected therewith, a tuft-setting and staple-driving mechanism deriving its actuation from one of said series of power-transmitting members, a vertically movable brush back support, adapted to be raised and lowered in timed relation to the movement of said tuft-setting and staple-driving mechanism through the medium of another of said series of power-transmitting members, and a pair of clamping blocks with which said support is normally in slidable relation, adapted to be projected into lock-

- ing position with respect to said support at a certain point in each cycle of operations of the machine, and to be thereafter positively retracted to their normal positions of 5 nonengagement with said support.
5. In a brush making machine, in combination with a vertically movable brush back support, a tuft-gathering and staple-driving mechanism, means for raising and lowering said support at each operation of the machine, means rendered active by the attainment by said support of its desired position with the respect to the staple-driving mechanism for locking the support in position 10 for a limited period, means for imparting a faltering movement to the support at a certain point in each cycle of operations, and a common power shaft with which the several parts are operatively connected, whereby 15 each is actuated to the degree and in the sequence desired.
6. In a brush making machine, the combination of a power shaft, a plurality of power-transmitting members deriving timed 20 actuation therefrom, a brush back support adapted to be projected and retracted by certain of said power-transmitting members in timed relation to the action of the other parts of the machine, a tuft-setting and 25 staple-driving mechanism actuated by certain other of said power-transmitting members, a tuft-locating member adapted to designate the point of impact on the brush back by the tuft-setting and staple-driving mechanism, means for positively locking said support 30 against movement at a certain point in each cycle of operations of the machine, and means for thereafter causing a faltering movement thereof with respect to the staple- 35 driving mechanism.
7. In a brush making machine, in combination with a tuft-gathering and setting means, a common power shaft, a vertically movable brush-back support, means for raising and lowering the same in timed relation 40 to the movement of the tuft-gathering and setting means, means also operating in timed relation to said tuft-gathering and setting means, whereby the brush-back support is locked against movement in either direction 45 between its raising and its lowering at each operation of the machine, and a tuft-locating member normally in the path of downward travel of the tuft-setting means, adapted to be displaced from such position during 50 the driving movement thereof.
8. A brush making machine, having in combination a tuft-setting and staple-driving mechanism, a tuft-locating member, a 55 movable brush back support, a common power shaft, means actuated by said power shaft whereby the brush back support is projected toward said tuft-setting and staple-driving mechanism to the desired degree before each operation thereof, means 60 also deriving actuation from said power shaft for locking the brush back support in position while the tuft is being driven into the brush back, and means for imparting a faltering movement thereto upon the release 65 of said support by said locking means.
9. A brush making machine, having, in combination with a frame, a power-shaft journaled therein, a tuft-setting and staple-driving mechanism operatively connected 70 with said shaft, a brush support capable of vertical movement with respect to said frame, a link and lever mechanism operatively connected with said power shaft and with said brush support, whereby it is raised 75 and lowered in timed relation to the movement of said staple-driving mechanism, a pair of clamping blocks normally out of engagement with said work support, and deriving actuation from said link and lever 80 mechanism, adapted to be projected into locking engagement about said work support at a certain point in each cycle of operations of the machine, and a tuft-locating member 85 whereby the blank may be properly positioned on the work support with respect to the tuft-setting and staple-driving mechanism.
10. In combination with a frame, a power shaft journaled therein, a plurality of series 90 of power-transmitting members operatively connected therewith, a work support adjustably supported in said frame, a pivoted lever member having one end connected with said work support, whereby the support 95 is raised and lowered by the movement thereof, the other end of said lever being operatively connected with one of said power-transmitting members, a pair of clamping blocks normally out of engagement 100 with said work support, means deriving their actuation from certain of said power-transmitting members whereby said clamping blocks are projected into locking engagement with said work support at a 105 certain period in each cycle of operations of the machine, and a tuft-setting mechanism operatively connected with certain others of said power-transmitting members, whereby it is operated in timed relation to the other 110 parts of the machine.
11. In combination with a frame, a work support adapted to be raised and lowered with respect thereto, a pair of clamping members arranged on opposite sides thereof, and means rendered active by the completion 115 of the raising and lowering movement of the work support, whereby said clamping members are first forced into clamping engagement therewith, and whereby they are afterward withdrawn therefrom to permit the lowering of the work support.
12. In combination with a frame, a stem member capable of being raised and lowered with respect thereto, means for actuating 120
- 130

said stem member in timed relation, a pair of clamping members adapted to be projected toward one another against said stem member whereby, in the interval between 5 the raising and lowering movement of said stem, it is locked in position, and connecting means between said locking means and said stem-actuating means for actuating said locking means synchronously with said 10 stem-actuating means.

13. In combination with a frame and a stem member slidably mounted therein, clamping means therefor, comprising a pair of clamping blocks adapted to be forced 15 thereagainst, a pair of actuating segments provided with cam faces to engage the peripheral portions of said clamping blocks, an inclosing casing therefor, means for rotating said casing and thereby forcing the 20 clamping blocks against and away from said slidable stem member, and means operating synchronously with said last mentioned means whereby said stem member is raised and lowered between successive clamping 25 movements of said blocks.

14. The combination, with an adjustable work support, and means for alternately raising and lowering the same, of a pair of clamping blocks adapted to engage opposing 30 sides of said work support during the period of time elapsing between the completion of the raising movement and the beginning of the lowering movement, said clamping blocks being adapted to be actuated against 35 said work support upon the attainment of such positions in the cycle of operations of the device by the means for actuating said work support, substantially as described.

15. In combination with a supporting 40 frame, a power shaft, a work support capable of limited movement with respect to the frame, a pivoted lever operatively connected with said power shaft for raising and lowering said work support in timed relation to the movements of the other parts of 45 the machine, and clamping members deriving timed actuation from the same source as said pivoted lever, whereby the work support is locked against movement at a certain 50 point in each cycle of operations of the machine.

16. In combination with a power shaft, a pivoted lever operatively connected therewith, a second pivoted lever operatively connected with said first mentioned lever, a work support adapted to be raised and lowered by the movement of a second pivoted lever, a spring for yieldingly holding said second lever and with it said work support 60 in raised position, a pair of clamping blocks for locking said work support in position, and operative connections between said clamping blocks and said first mentioned lever whereby said blocks are projected and 65 retracted with respect to said work support

in timed relation to the cycle of operations of the machine.

17. In combination a slidable stem member, a pair of clamping segments engaging with their straight edges on each side thereof, an inclosing cup member provided with interiorly located wedge surfaces, and means for rotatively actuating said cup member, thereby forcing said segments into clamping engagement with said stem member 70 through the engagement of said wedge surfaces against the peripheral portions of said segments, and for synchronously actuating said stem member relatively thereto.

18. In combination with a slidable stem member, means for positively raising and lowering the same, a pair of clamping segments slidably engaging the same with their straight edges, a cup member engaging about said segments, a pair of wedge members interposed between the peripheral portions of said segments and the interior peripheral portion of said cup member, and incapable of relative movement with respect to said cup member, and means deriving its 80 actuation from the movement of said means for raising and lowering the stem, whereby at a certain point in the cycle of operations of the device said cup member is rotated, thereby forcing said segments into clamping 85 engagement with said stem member through the medium of said wedge members.

19. In combination with a power shaft, a pivoted lever operatively connected therewith, an adjustable work support, a second lever operatively connected with said first named lever and with said work support whereby said work support is raised and lowered, a pair of clamping blocks adapted 100 to be forced toward one another into locking engagement said work support at a certain point in each cycle of operation of the machine, and means connecting said clamping member with said first named lever whereby the same is thrown into engagement with said work support at the desired 105 time.

20. The combination, with a frame, of a cupped casing member supported thereby in position of limited rotatability, a pair of cam segments arranged interiorly thereof and rotatable therewith, a pair of clamping blocks arranged therewithin, a work support passing through said casing and normally slidable with respect to the opposed straight edges of said clamping blocks, a common power shaft, and power-transmitting members operatively connecting said shaft with said casing members and with 115 said work support, whereby the work support is moved relatively to the casing and its contained parts, and whereby the casing is thereafter rotated to force said clamping blocks into locking engagement with said 120 work support.

21. In a brush making machine, in combination with a supporting frame, a work support vertically adjustable with respect thereto, a pair of clamping blocks pivotally supported from said frame, between which blocks said support slidably engages, a pivoted lever by whose movement said work support is raised and lowered, a second lever member by which said clamping blocks are projected against and away from said work support in timed relation to the cycle of movement thereof, and actuating members whereby the movement of said lever member is caused in timed relation to one another. 15
22. The combination of a frame, a vertically movable stem member, a pair of clamping blocks between which said stem member slidably engages, a casing provided with internally located wedge faces adapted to engage the clamping blocks to effect their projection and retraction with respect to said stem member, and an actuating member for rotating said casing to move said clamping blocks in timed relation to the movement of said stem member. 20
23. In combination with a frame member, a casing member provided with internally arranged wedge faces pivotally supported thereby, a pair of clamping blocks arranged within said casing in position to be actuated toward and away from one another by the 30
- action of said wedge faces on their curved peripheral portions, a stem member slidably engaging between said clamping blocks when the same are in retracted position with respect to one another, and adapted to be held from movement in either direction when said clamping blocks are projected thereagainst, and means deriving actuation from a common source whereby the several parts are actuated in timed relation to one another. 35
24. In combination with a pivotally supported apertured casing provided with internally arranged cam faces, a stem member 45 slidably engaging through the apertures in the casing, a pair of clamping blocks arranged within said casing, between which said stem member passes, means for raising and lowering said stem member with respect to said casing and its contained parts and for maintaining it against axial displacement, and means for imparting limited rotative movement to said casing, thereby causing the projection of said clamping blocks 50 against said stem member. 55

In testimony whereof, I sign this specification in the presence of two witnesses.

WILLIAM G. LIEBIG.
